(57) **CLAIM**

The ornamental design for the eyewear, as shown and described.

DESCRIPTION

FIG. 1 is a top-front-left perspective view of eyewear according to the present invention.

FIG. 2 is a bottom-rear-right perspective view of the eyewear.

FIG. 3 is a left side elevational view of the eyewear, with the right side elevational view being a mirror image of the left side elevational view.

FIG. 4 is a top plan view of the eyewear.

FIG. 5 is a front elevational view of the eyewear.

FIG. 6 is a bottom plan view of the eyewear; and,

FIG. 7 is a rear elevational view of the eyewear.

The broken lines illustrate portions of the eyewear that form no part of the claimed design.

1 Claim, 5 Drawing Sheets
